(57) **CLAIM**

The ornamental design for a transurethral needle ablation device, as shown and described.

DESCRIPTION

FIG. 1 is a perspective view of the transurethral needle ablation device showing our new design.

FIG. 2 is a right side view thereof.

FIG. 3 is a left side view thereof.

FIG. 4 is a top view thereof.

FIG. 5 is a bottom view thereof.

FIG. 6 is a front view thereof; and,

FIG. 7 is a rear view thereof.

The broken lines immediately adjacent to the shaded area represent the boundaries of the claimed design while all other broken lines illustrate the portions of the design that form no part of the claim.
